PRIMING MECHANISM FOR CENTRIFUGAL PUMPS

Filed Aug. 2, 1926

UNITED STATES PATENT OFFICE

ARTHUR B. SINGLETON, OF DETROIT, MICHIGAN, ASSIGNOR TO NASH ENGINEERING COMPANY, OF SOUTH NORWALK, CONNECTICUT, A CORPORATION OF CONNECTICUT

PRIMING MECHANISM FOR CENTRIFUGAL PUMPS

Application filed August 2, 1926. Serial No. 126,434.

This invention relates to mechanism for priming a centrifugal pump, particularly of the impeller type. Such pumps when operating under a negative head lose their pumping capacity as soon as air is admitted to the pump chamber, which very often happens when the pump is used for handling an irregular or inconsiderable flow of liquid.

It is the object of my invention to provide improved priming mechanism for rendering the pump again operative, said priming mechanism being automatically limited in its action to the requirements of the system at any particular time.

15 A further object is to provide a construction by which dirty or gritty water will be prevented from entering the priming air pump and will be handled only by the centrifugal water pump.

20 Another object of my invention is to provide mechanism for priming a centrifugal water pump which will automatically prevent flooding of the air pump after the water pump has become fully operative.

25 In the preferred form of my invention, the priming air pump is rendered partially inoperative when the water level above the centrifugal intake reaches a certain predetermined point, and thereafter maintains a degree of vacuum merely sufficient to maintain 30 the water level for the centrifugal pump without causing a further rise of the water.

35 My invention further relates to arrangements and combinations of parts which will be hereinafter described and more particularly set forth in the appended claims.

40 A preferred form of the invention is shown in the drawing, which is a side elevation, partly in section, of a pumping apparatus embodying my invention.

45 Referring to the drawing, I have shown a separating tank 10 having an inlet pipe 11 from a water supply which is commonly at a lower level than the tank 10. A centrifugal pump 12 has its inlet 13 extending into the lower part of the tank 10 and has a discharge pipe 14 through which water is discharged past a check valve 15 to any desired point of delivery.

50 A priming air pump 20 is provided for the

pumping apparatus, said air pump being connected by pipes 21 and 22 to the top of the tank 10 and by additional pipes 23 and 24 to the casing of the centrifugal water pump 12. A check valve 25 is inserted in the connections to the pump 12 for a purpose to be described; and an additional branch pipe 26 connects the pipe 23 to a chamber or receptacle 30 in which is mounted a valve 31 controlled by a float 32.

55 The chamber 30 is connected by a pipe 33 to the side of the tank 10 and is also provided with an air inlet pipe 34 controlled by the valve 31.

60 The vacuum pump 20 is additionally provided with an air discharge pipe 36 and also preferably has a separate water supply pipe 37 when the pump 20 is of the type using water for its pumping action. An additional check valve 38 is also preferably placed in 70 the vacuum connection 21.

65 Having described the details of construction of my improved pumping apparatus, the functions and method of operation thereof are as follows:

75 It is well known that a centrifugal pump, whenever it loses its water supply, becomes air bound and that it is very difficult and practically impossible to cause such a pump to resume operations until the pump has 80 been primed by withdrawing the air and admitting water to the pump casing. A primary function of the vacuum pump 20 is the priming of the casing of the centrifugal pump 12 by exhausting the air therefrom.

85 The pump 20 serves an additional purpose, as it acts through its connection 22 to assist the centrifugal pump in exhausting the air from the tank 10, causing the water to be pumped to rise into the tank 10 through the inlet pipe 11.

90 It is desirable, however, to limit the operation of the air pump 20, as otherwise some of the water from the tank 10 may enter the air pump through the connection 22 and the pipe 21. Certain types of air pump are seriously injured by permitting any considerable quantity of water to enter the pump, and other types of air pumps, such as those using water for the pumping action, while not in-

jured by the admission of clear water, may be seriously damaged by the admission of water containing grit or sand, such as is frequently drawn into a separating tank as indicated at 10 and such as may be readily handled without injury by a centrifugal pump.

I prevent the flow of water to the pump 20 by the operation of the float controlled valve 31. As the water in the tank 10 reaches the predetermined level indicated by the line

XX, the float 32 rises, opening the valve 31 and admitting air through the pipe 26 to the suction pipe 21 of the vacuum pump 20. The pump 20 is thus limited in its operation and consumes less power than would otherwise be required, as the degree of vacuum is maintained at a predetermined point and never exceeds the requirements of the system.

When the water level falls below the line XX, the valve 31 again closes and the air pump increases the vacuum until the water level is again normal.

Whenever air is admitted through the valve 31, the check valve 25 immediately closes, thus preventing the air from flowing downward through the pipe 24 and venting the centrifugal pump 12. The check valve 38 prevents flow of air to the apparatus when the vacuum pump 20 is not in operation.

I have thus provided means by which the vacuum pump not only primes the centrifugal pump, but also assists in exhausting the separating tank 10, and at the same time I have provided means for limiting the action of the vacuum pump when the water level is normal and for maintaining the water level in the tank 10 at a point where sand or gritty water cannot be drawn over into the vacuum pump and injure the mechanism thereof.

Having thus described my invention and the advantages thereof, I do not wish to be limited to the details herein disclosed otherwise than as set forth in the claims, but what

45 I claim is:—

1. Pumping apparatus comprising a separating tank having an inlet connected to a source of lower lever water supply, a centrifugal water pump having a casing separate from said tank, said pump being connected to withdraw water from said tank, an air pump having a connection to said tank and to said centrifugal pump casing, whereby to exhaust air therefrom, a float-controlled valve effective to admit air to partially disable said air pump when the water level in the tank reaches a predetermined level, and a check valve to prevent reverse flow of air through the vacuum connections to the centrifugal pump when said float valve is opened.

2. Pumping apparatus comprising a separating tank having an inlet connected to a source of lower level water supply, a centrifugal water pump having a casing separate from said tank, said pump being connected to

withdraw water from said tank, an air pump having a connection to said tank and to said centrifugal pump casing, whereby to exhaust air therefrom, a float-controlled valve effective to admit air to partially disable the air pump when the water level in the tank reaches a predetermined level, and a check valve effective to prevent reverse flow of air through the connections to said tank and to said centrifugal pump when the air pump is inoperative.

3. Pumping apparatus comprising a tank having an inlet connected to a source of lower level water supply, a centrifugal water pump having a casing separate from said tank, said pump being connected to withdraw water from said tank, an air pump connected to exhaust air from said tank and to cause flow of water from the lower level thereto, a branch connection from said air pump to said centrifugal pump casing for exhausting air therefrom, and means to vent said air pump when the water in said tank reaches a predetermined level.

4. Pumping apparatus comprising a tank having an inlet connected to a source of lower level water supply, a centrifugal water pump separate from said tank and connected to withdraw water from said tank, an air pump connected to exhaust air from said tank and from the centrifugal pump, a float control valve effective to admit air to partially disable said air pump as the water level in the tank reaches a predetermined level, and means to prevent reverse flow of air through the vacuum connections to the centrifugal pump upon opening of the float valve.

5. Pumping apparatus comprising a tank having an inlet connected to a source of lower level water supply, a centrifugal water pump separate from said tank and connected to withdraw water from the tank, an air pump connected to exhaust air from said tank and from said centrifugal pump, a float control valve effective to admit air to partially disable the air pump when the water level in the tank reaches a predetermined level, and means effective to prevent reverse flow of air through the connections to the tank and to the centrifugal pump when the air pump is inoperative.

In testimony whereof I have hereunto affixed my signature.

ARTHUR B. SINGLETON.
